UNITED STATES PATENT OFFICE.

JEANNOT W. KENEVEL, OF PHILADELPHIA, PENNSYLVANIA, ASSIGNOR TO WILLIAM H. MITCHEL, OF MEDIA, PENNSYLVANIA, FRANK W. TUSSEY, OF CAMDEN, NEW JERSEY, AND JOHN R. BONINE, OF PHILADELPHIA, PENNSYLVANIA, TRUSTEES.

ELECTROLYTIC APPARATUS.

1,000,608.

Specification of Letters Patent. Patented Aug. 15, 1911.

Application filed September 22, 1910. Serial No. 583,159.

To all whom it may concern:

Be it known that I, JEANNOT W. KENEVEL, a citizen of the United States, residing in the city of Philadelphia, county of Philadelphia, and State of Pennsylvania, have invented certain Improvements in Electrolytic Apparatus, of which the following is a specification.

My improvements in electrolytic apparatus are designed for destroying animalcules and coagulating solids held in water in an efficient and economical manner.

The nature and characteristic features of my improvements are fully disclosed in the following description and the accompanying drawings in illustration thereof.

In the drawings, Figure 1 is a sectional plan view of apparatus embodying features of my invention; Fig. 2 is a side elevation 20 of the same with parts broken away; Fig. 3 is a transverse sectional elevation taken on the line 3—3 of Fig. 1; and Fig. 4 is a diagrammatic view representing in plan the electrolytic apparatus in combination with 25 current regulating means used therewith.

The apparatus, as illustrated in the drawings, comprises a chamber 1 having an insulating lining 1^a, the chamber having suitably a cast iron body lined with porcelain.

30 The chamber 1 has its respective ends connected by the ducts 2 and 3 with the conduit 4 having the section 4^a, by which liquid flowing in the conduit can be passed either through or around the chamber, to which 35 end valves 5 and 6 control the flow through the respective ducts 2 and 3 and a valve 7 controls the flow through the section 4^a.

The chamber 1 is provided with the several hoods or covers 1' having the porcelain 40 linings 1^a, the body of the chamber having the bearings 1^b and 1^c and the hoods having the flanges 1^d and 1^e secured thereon by bolts 8.

The respective hoods 1' have set therein 45 the insulating bushings 9 and 10 through which pass the binding posts 11 and 12, these posts having conducting collars 11' and 12' fixed thereto within the respective hoods.

Conducting rods 13 and 14, passing 50 through and supported by the respective

collars 11' and 12', have the respective electrodes 15 and 16 sleeved thereon, the electrodes being spaced by insulating collars 11^a and 12^a acting in conjunction with the collars 11' and 12'. Nuts 13' and 14' are 55 screwed on the ends of the respective rods 13 and 14 so as to clamp the electrodes and collars firmly together.

The respective sets of electrodes 15 and 16 have their tops cut at an inclination so 60 that the rod shall pass through the high corners of the electrodes supported thereby above the coacting electrodes of the set.

The several binding posts 11 have a conductor 17 connected therewith and the several binding posts 12 have a conductor 18 connected therewith. These conductors are connected through the cut-out 19 with the respective conductors 20 and 21, the conductor 20 containing the lamps 22 to provide 70 resistance and the conductor 21 containing the switch 23 for controlling the circuit. The conductors 20 and 21 are connected through the cut-out 24 with the line conductors 25 and 26. 75

The valve 7 being closed and the valves 5 and 6 open, the water to be treated flows from the conduit 4, through the duct 2 and vessel 1, between the electrodes 15 and 16 of the respective sets of electrodes, to the duct 80 3 and thence to the conduit 4 beyond the valve 7, the water being baffled and directed in tortuous courses by staggering the electrodes of the several sets. As the water flows through the vessel, it is subjected to 85 electrolytic action, transverse to its course, of the character required, the electric current being regulated by regulating the resistance.

Having described my invention, I claim: 90

1. An electrolytic apparatus comprising a chamber having a porcelain lining, several hoods for covering sections of said chamber, several sets of electrodes, and conducting means whereby a set of electrodes is supported in said chamber by each of said hoods. 95

2. An electrolytic apparatus comprising a chamber having oppositely disposed inlet and outlet ducts, several groups of elec- 1

trodes disposed in said chamber, each of said groups comprising coacting parallel plates and the plates of the several groups being staggered relatively, several hoods for 5 said chamber, and means whereby each of said hoods supports one of said groups of plates.

In witness whereof I have hereunto set my name this 20th day of September, 1910, in the presence of the subscribing witnesses. 10

JEANNOT W. KENEVEL.
